George C. Firme and Peter Endres
by Hubert W. Jenner, Attorney

UNITED STATES PATENT OFFICE.

GEORGE C. HUME AND PETER ENDRES, OF CHILTON, WISCONSIN.

LIFTING APPARATUS.

Application filed April 4, 1924. Serial No. 704,178.

To all whom it may concern:

Be it known that we, GEORGE C. HUME and PETER ENDRES, citizens of the United States, residing at Chilton, in the county of Calumet and State of Wisconsin, have invented certain new and useful Improvements in Lifting Apparatus, of which the following is a specification.

This invention relates to apparatus for use in hospitals for raising patients from their beds so that their bedding can be changed, and for other similar purposes; and it consists of a portable framework and a frame provided with bands of flexible material for supporting the patient and raising him above his bed, as hereinafter fully described and claimed.

In the drawings, Figure 1 is a side view of an apparatus constructed according to this invention. Fig. 2 is an end view of the same looking from the left in Fig. 1. Fig. 3 is a plan side view of the end portions of one of the bands of flexible material, and is drawn to a larger scale. Fig. 4 is a plan view of the same.

The portable framework has a horizontal bar 6 at its top of sufficient length to extend longitudinally over the bed in which the patient is resting. The ends of the bar 6 are connected to vertical members 7 by quarter bend pieces 8, and all the framework is preferably tubular for lightness and strength. The vertical members 7 are secured and braced to the end portions of a rectangular frame 8' arranged horizontally and provided with legs 9 which rest on the floor. The framework is proportioned so that it can be stood over the bed and the patient in it, and so that it can be moved about from bed to bed with great facility.

A rectangular main frame 10 is provided, of greater length and width than the body of the patient, and is adapted to be placed over him as he lies in the bed so that it rests on the bed around him. An auxiliary frame 12 is arranged inside one end portion of the main frame, and one end of it is pivotally connected with the middle part of the main frame in any approved way, so that it will not slip. The main frame has bails 14 pivoted to its end portions, and 15 are lifting straps or cords pivotally connected to the middle parts of the bails, and passing over hoisting tackles 16 which are suspended from the end portions of the horizontal top bar 6. The lifting tackles

are preferably self-supporting tackles provided with straps, instead of the usual cords, but any approved lifting devices may be used. Separate lifting devices 15 are provided so that each end of the frame can be raised and lowered independently of the other.

The main frame 10 and the auxiliary frame 12 have pins 18 which project upwardly from their sides, and 20 are bands of flexible material, such as canvas, which are adapted to be passed under the body of the patient and sustain him in the frame. A hoisting tackle 21 is also secured to the top bar 6 and to the free end portion of the auxiliary frame, so that it may be supported at any suitable angle with the horizontal main frame 10 to suit the head and shoulders of the patient.

Each band 20 has a fastening plate 24 at one end having a hole 25 for engaging with one of the pins 18, and each plate has also a long slot 26. The end portion of the band is passed downwardly through the slot and is looped around an anchor rod 27, and is then folded double and is passed upwardly through the slot. The band is adjusted in length by arranging the rod 27 at different distances from its extreme end. As the doubled portion 28 is pressed on the plate by the weight of the patient on the upper stretch of the band, and as the rod 27 is longer than the slot, the band cannot slip after being adjusted in length.

The other end portion of the band is provided with a fastening plate 30 similar to the plate 24, and it has a similar hole and slot, and is connected to the band by a similar anchor rod. A loop-shaped handle member 31 is pivoted in an eye 32 on the outer end of the plate 30, and is used for drawing the band taut, and connecting the plate to its pin. The lever 31 is passed under the body of the patient and over the side bar of the frame, and is then pressed downwardly in contact with the bar until the hole in the plate slips over the pin. In Figs. 3 and 4 the handle member is shown in a raised position for clearness of illustration. When the handle member is slid under the patient and onto the side bar of the frame its loop clears the pin 8. The free end portion of the handle member 31 is then pressed downwardly under and against the frame bar, so that it operates as a lever having the frame bar as a fulcrum.

The handle member slides on the frame bar and draws upon the band 20 until the hole in the plate 30 slips over the pin 18, both plates 24 and 30 being at that time substantially horizontal and the band 20 taut. The plate 30 is raised a little by hand, if necessary, to let the eye 32 slide over the top of the pin. The plates then slip a little to the inclined positions shown. The use of the handle member as a lever enables the bands to be drawn very taut. When they sag into loops under the patient, the patient cannot be supported in an inclined position without great discomfort. In this manner the body of the patient is supported in substantially the same plane as the frame, and when the frame is raised by the hoisting tackle, and the whole apparatus is slid clear of the bed, the patient may be supported at an angle to the horizontal, as well as horizontally, which is sometimes desirable.

The apparatus is subsequently replaced over the bed, and the patient is lowered onto it. This use of this apparatus saves badly injured patients from much pain and discomfort.

What we claim is:

1. In an apparatus for raising and supporting patients, a main framework, a frame for the patient provided with pins which project upwardly from one of its sides, bands of flexible material provided with means for connecting them to the other

side of the frame, end plates connected at one end to the said bands and provided with holes for engaging with the said pins between their ends, handle members pivoted to the free ends of the end plates and adapted to be used as levers, with the frame bar as a fulcrum for drawing the bands taut and slipping the holes of the end plates over the pins, and lifting devices supporting the said frame in the main framework.

2. An apparatus as set forth in claim 1, the said end plates having eyes at their free ends, and the said handle members being loop-shaped and being pivoted in the said eyes.

3. In a frame for supporting a patient, side bars one of which has upwardly projecting pins, bands of flexible material provided with means at one end for attaching them to the other side bar of the frame, plates connected to the other ends of the flexible bands and having holes for engaging with the said pins, and handle members pivoted to the said plates and formed of rigid material and adapted to be used as levers, with the frame bar as a fulcrum, for drawing the flexible bands taut and slipping the said holes over the pins.

In testimony whereof we affix our signatures.

GEORGE C. HUME.
PETER ENDRES.
